UNITED STATES PATENT OFFICE.

JOHN D. WARD, OF BUFFALO, NEW YORK.

DESIGN FOR A SEAMING AND CUTTING TOOL.

SPECIFICATION forming part of Design No. 32,876, dated June 26, 1900.

Application filed October 14, 1899. Serial No. 733,679. Term of patent 3½ years.

To all whom it may concern:

Be it known that I, JOHN D. WARD, a citizen of the United States, residing at Buffalo, in the county of Erie and State of New York, have invented and produced a new and original Design for Seaming and Cutting Tools, of which the following is a specification, reference being had to the accompanying drawings, showing a part thereof.

10 In the drawings, Figure 1 is a plan or face view of my design for a seaming and cutting tool, and Fig. 2 is an edge view of the same.

Referring to the drawings, it will be seen that the design is cut from a flat metal strip, the body of which is shaped into a handle 1, the corners 2 of which are curved, as shown in the drawings. Projecting from one end of this handle 1 are the prongs 3 and 4, upon which the cutting-blades are formed, the 15 prong 3 being pointed and the end of the prong 4 being formed by an outwardly-curved quarter-turn of the inner edge of the prong 4. The neck 5 or portion connecting the prongs 3 and 4 with the handle 1 is slightly 20 curved outward and is provided with an ori-

face 6 in its center. A second orifice 7 is made in the opposite end of the handle 1.

As seen in the drawings, the design is entirely cut in the face of the plate, the sides presenting a flat plane showing an edge view 30 of substantially the same thickness along its entire length.

The leading feature of my design consists in a seaming and cutting tool formed from a flat plane and cut to represent a handle, with 35 projecting prongs extending from one end thereof.

Having thus described my design, what I claim, and desire to secure by Letters Patent, is—

40 The design for a seaming and cutting tool, substantially as herein shown and described.

In testimony whereof I have hereunto signed my name to this specification in the presence of two subscribing witnesses.

JOHN D. WARD.
